UNITED STATES PATENT OFFICE

2,456,512

MUFFLER FOR INTERNAL-COMBUSTION ENGINES

George V. Johnson, Portland, Oreg., assignor to
Hyster Company, Portland, Oreg., a corporation
of Oregon

Original application December 31, 1943, Serial No.
516,405. Divided and this application August
17, 1945, Serial No. 611,082

3 Claims. (Cl. 180—54)

1

The present invention relates to mufflers for internal combustion engines, and is particularly concerned with a muffler construction adapted to be utilized upon automotive vehicles of the lift truck type.

This application is a division of my prior application Serial No. 516,405, filed December 31, 1943, for Lift trucks, which has now issued as Patent No. 2,387,077, dated October 16, 1945.

One of the objects of the invention is the provision of an improved type of muffler for internal combustion engines, which is so constructed that there is assurance that no sparks will issue from the exhaust which passes through the muffler, yet which has a minimum amount of back pressure and which accomplishes a satisfactory muffling of the noise of the engine.

Another object of the invention is the provision of an improved muffler for internal combustion engines which is simple in construction and which may be embodied as a part of the chassis of a lift truck so that it may be manufactured at a minimum cost.

Another object of the invention is the provision of an improved muffler for internal combustion engines which is very simple, including only a receptacle with a body of extinguishing liquid, such as water, an inlet pipe which directs the exhaust gases toward the surface of the water, and an outlet pipe located remote from the end of the inlet pipe.

Another object of the invention is the provision of an improved muffler of the class described which is simple, capable of economical construction, adapted to be used for a long period of time without repair or replacement of its parts, and which absolutely assures that no sparks will issue from the exhaust pipes.

Another object of the invention is the provision of an improved lift truck chassis structure which includes a built-in pair of mufflers for the internal combustion engine by means of which all sparks issuing from the exhaust are extinguished.

Other objects and advantages of the invention will be apparent from the following description and the accompanying drawings, in which similar characters of reference indicate similar parts throughout the several views.

Referring to the two sheets of drawings accompanying this specification.

Fig. 1 is a side elevational view in partial section, showing a lift truck equipped with an internal combustion engine and with a muffler embodying my invention;

Fig. 2 is a top plan view of the lift truck;

2

Fig. 3 is a sectional view, taken on the plane of the line 3—3 of Fig. 2, looking in the direction of the arrows.

Referring to Fig. 1, 10 indicates in its entirety a lift truck embodying my invention. In this lift truck the chassis is indicated at 11, and the chassis is provided with a pair of front driven wheels 12, 13 and a rear steered wheel 14. The structure of the rear steered wheel mechanism is preferably as disclosed in my prior Patent No. 2,337,109, issued December 21, 1943. The chassis is provided with an internal combustion engine 15 for driving the vehicle, and at its front end it carries a suitable upright framework 16, which is provided with an upwardly telescoping frame 17 by means of which it may be extended.

The telescoping framework 16, 17 carries a vertically movable carriage 18 with a pair of load arms 19, by means of which a load may be lifted, the load being retained by tilting the upright frame to the right hand dotted line position shown in Fig. 1.

The chassis of the vehicle is preferably made of cast metal, such as cast steel; and at its rear end the chassis is provided with a vertically extending bearing 20, which supports a vertical trunnion carried by the counterweight 21 which carries the steered wheel 14.

The outer portion of the chassis may comprise a pair of side panels 22 joined at the front by a transversely extending frame member 44 which also serves as a floor board and joined at the rear by a vertically extending partially cylindrical end wall 45. At the top and to the rear of the frame member 46, the side panels 22 are also preferably joined by a top panel 46. The side panels 22 carry a pair of muffler receptacles 23, 24 that form an integral part of the chassis. The muffler receptacles 23, 24 may be substantially rectangular in side and end elevation and in plan, except that the rear end has a filling extension 25, with an opening closed by a filling plug 26.

Each of the muffler receptacles or housings 23, 24 is thus provided with a bottom wall 27, a pair of side walls 28, 29, and a top wall 30. Each side wall is an integral part of each side panel 22. Thus, each side panel serves as one outer wall of the chassis and also as one side wall of each muffler receptacle. Each receptacle also has a front wall 31 and rear wall 32.

Exhaust from the internal combustion engine is preferably connected by means of an exhaust pipe to the muffler; and in the present case the engine has a pair of exhaust pipes, indicated at 33, 34, 55 extending from the two banks of cylinders to the

respective mufflers 23 and 24. The exhaust pipes 33, 34 may extend diagonally into the muffler chambers 35, 36, and are bent downwardly at 37 so that the open ends 38 point toward the surface 39 of the body of water 40 in each muffler.

The top 30 of each muffler housing is preferably provided with a thickened portion 41, which has a threaded bore for receiving the outlet pipes 42, 43. Each outlet pipe extends upwardly and is preferably turned at substantially a right angle so that its open end 44 opens horizontally backwardly with respect to the vehicle.

The level 39 of the liquid 40, such as water, in each muffler is preferably kept substantially below the open ends 38 of the exhaust pipes.

The operation of the muffler is as follows: The exhaust gases, carbon sparks, etc. are discharged from the open end 38 of the exhaust pipe at high velocity directly toward the free surface of the water 40. Any burning particles are driven into the water and extinguished.

As the exhaust gases at high velocity pass out of the pipes 33, 34 into the exhaust chamber 35, these gases are permitted to expand freely into the larger space provided, and the velocity energy is dissipated in this chamber. Successive waves of pressure are created in the chamber, which are discharged through the tail pipes 42, 43 to atmosphere, and is found that the noise of the explosion of the engine is substantially muffled by the use of this structure.

Due to the use of water there is practical assurance that no sparks will pass out of the tail pipes, and the construction is also so arranged, with the tail pipes at the top, that water is not blown from the muffler, thus permitting the use of the mufflers for a long period of time without refilling.

The explosive energy of the gases coming from the exhaust pipes is also absorbed in blowing or splashing the water about, which also tends to absorb the noise, somewhat like a resilient cushion, since the free surface of the water may be depressed momentarily by the force of the exhaust gases at each explosion.

The present muffler construction is simple, yet it is very effective. It requires very little attention. It may be used for a long period of time without necessity for repair or refilling. Necessity for refilling immediately becomes evident from the increased noise when the water has all been used up by evaporation. Sparks are all extinguished. By means of this structure the present lift truck may be used with absolute safety in warehouses and other enclosed spaces where inflammable materials may be present.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In an automotive vehicle the combination of a chassis provided with a pair of side panels

joined by a top panel, each of said side panels carrying a muffler housing integrally formed therewith comprising side walls, bottom wall, and top wall, each of said side panels serving as one outer wall of the chassis and also as one side wall of each muffler housing, said housing containing a predetermined amount of extinguishing liquid, an exhaust pipe extending into said housing into proximity with the free surface of said liquid, and a tail pipe extending out of said housing adjacent the top thereof.

2. In an automotive vehicle the combination of a chassis provided with a pair of side panels joined by a top panel, each of said side panels carrying a muffler housing integrally formed therewith and comprising side walls, bottom wall, and top wall, each of said side panels serving as one outer wall of the chassis and also as one side wall of each muffler housing, said housing containing a predetermined amount of extinguishing liquid and having an exhaust pipe extending into said housing toward and into proximity with the free surface of said liquid and having a tail pipe extending out of said housing adjacent the top thereof, said exhaust pipe opening at substantially right angles to the free surface of the liquid, whereby burning particles and sparks are directed into the extinguishing liquid.

3. In an automotive vehicle the combination of a chassis provided with a pair of side panels joined by a top panel, each of said side panels carrying an integral muffler housing comprising side walls, bottom wall, and top wall, each of said side panels serving as one outer wall of the chassis and also as an upper support for each muffler housing, said housing containing a predetermined amount of extinguishing liquid and having an exhaust pipe extending into said housing into proximity with the free surface of said liquid and having a tail pipe extending out of said housing adjacent the top thereof, said exhaust pipe opening at substantially right angles to the free surface of the liquid, whereby burning particles and sparks are directed into the extinguishing liquid, said mufflers being mounted adjacent the rear of the chassis, and said muffler housings being provided with an upwardly open filling opening having a closure therefor.

GEORGE V. JOHNSON.
